FOLDING CANOPY FOR VENDING STAND TRAILERS

Socrates J. Schantz, St. Louis, Mo.

Application April 1, 1957, Serial No. 649,974

9 Claims. (Cl. 160—62)

This invention relates to folding canopies, and in particular is concerned with a folding or collapsible canopy for vending stands, which are mounted upon a trailer and in which the canopy may be collapsed to a locking position where it closes up the open windows of the stand.

This invention finds particular usefulness in providing a canopy for small vending stands which are transported from one location to another. Such vending stands may be mounted upon a trailer in well known fashion which because of their mobility are adapted to service any desired locality such as in the neighborhood of schools, athletic contests, etc., where people congregate and patronize the stand. Such stands conventionally vend hot dogs, soft drinks, ice cream and the like. In the past, it has been conventional to vend from an opened window at one side of the stand. It is quite desirable to provide a top canopy or roof to protect the customer from the direct rays of sunlight or possible inclement weather. Also, through the use of a projecting roof the interior of the stand may be protected against the hazards of weather.

This invention provides a folding canopy which can be easily set up to the assembled position in a matter of minutes after the stand has been located in the desired position. The canopy is of a rectangular configuration and has what may be termed an overlying roof portion and side members which aid in the supporting of the roof member. By means of the particular construction of the folding canopy, the roof member is further adapted to be collapsed from the canopy assembled position in such a manner that it may be locked over the vending window to a so-called boarding up position. This is quite desirable when the vending stand is closed down either over night to protect the contents or when the vending stand is moved to another vending location.

The construction of the vending stand canopy is simple in nature and rugged so that it will readily withstand the rigors of transportation. As a very desirable feature, it may be knocked down or collapsed from the canopy position to the window boarding up position in a very short period of time without the requirement of any special tools. Conversely, the canopy may be assembled to the final canopy position from the boarded up position in a very short period of time by a reversal of the operation.

Accordingly, it is a primary object of this invention to provide a collapsible canopy for vending stands which is rugged in construction and simple to assemble.

It is a further object of this invention to provide a collapsible canopy for vending stands and the like comprising a roof member and supporting side members in which the roof member may be collapsed to cover a vending window and very simply locked in place.

Yet another object of this invention is to provide a vending stand with a folding canopy comprised of a hinged rigid roof member which can be assembled to a canopy position and collapsed to a venting window covering position and in which side members of a hinged

2

nature are provided to support the canopy roof member in the canopy assembled position.

Still another object of this invention is to provide a hinged collapsible canopy for vending stands which can be set up to a canopy position or knocked down to a vending window covering and locking position which is simple in construction and easy to operate by unskilled operators without the requirement of any special tools.

Further objects of this invention will appear in the detailed description which follows and will be further apparent to those skilled in the art.

For the purpose of illustration there is shown in the accompanying drawings a preferred embodiment of this invention. This embodiment is shown for particular use with vending stand but it is to be understood that the canopy can be used in other applications and is not limited thereto.

In the drawings:

Figure 1 is a side view of a vending stand equipped with the folding canopy shown in the knocked down and vending window covering position;

Figure 2 is a view in side elevation taken similarly to Figure 1 showing the canopy in the canopy assembled position;

Figure 3 is a view in front elevation of a vending stand with the canopy in an assembled position taken from the left side of Figure 2;

Figure 4 is an enlarged view in section taken on the line 4—4 of Figure 1 showing the arrangement of the members of the canopy in the knocked down position;

Figure 5 is an enlarged view in section taken on the line 5—5 of Figure 2 showing the interengagement of the canopy roof member with the side supporting member in a locked position of the canopy assembly;

Figure 6 is an enlarged view in section taken on the line 6—6 of Figure 1 which shows the retaining means for a supporting rod used with the supporting side member;

Figure 7 is an enlarged view in section taken on the line 7—7 of Figure 1 showing a retaining means for the terminal portion of the side member supporting rod;

Figure 8 is an enlarged fragmentary plan view of one end of the assembled canopy showing the means for supporting the canopy and the interengagement of the roof and side supporting members;

Figure 9 is an enlarged fragmentary view in elevation taken at the right side of Figure 1 showing the bottom right hand corner of the roof and the right hand end of the roof supporting member locked to the vending stand in the vending window covering position;

Figure 10 is a view in section taken on the line 10—10 of Figure 9 showing a locking device for retaining the roof supporting member of the canopy against the vending stand;

Figure 11 is a view in section taken on the line 11—11 of Figure 9 showing further details of construction of the locking device for retaining the canopy in a vending window covering position;

Figure 12 is an enlarged fragmentary view taken at the upper right hand corner of Figure 8 showing the means for locking the roof supporting member to one of the side supporting members by means of a notched construction; and

Figure 13 is a view in section taken on line 13—13 of Figure 12 showing further details of construction of the means for locking the roof supporting member upon one of the side supporting members.

In Figures 1, 2 and 3, the vending stand is generally indicated by the reference numeral 20. It may be supported on a conventional trailer in a manner well known to the art so that it may be transported from one location to another. The vending stand is provided with two side

windows 21 and a pair of folding canopies which are adapted to be assembled in a raised position as shown in Figure 3. The canopies are designated in Figure 3 by the reference numerals 22 and 23.

The vending stand 20 has four corner posts 24 which are identical in construction. For the purpose of reinforcement and to provide a base for the canopy, side braces 25 and end braces 26 are connected between the posts to provide rigidity to the stand. As will be apparent below, the side brace 25 and the corner posts 24 provide all the structure needed to retain the canopy and to provide for the locking of the canopy either in the canopy assembled position or in the knocked down window covering position shown in Figures 1 and 3 respectively.

Both the canopies 22 and 23 are identical in construction and for the purpose of description only the canopy 23 will be described. As best shown in Figures 1, 5 and 8, the canopy 23 comprises as its essential components a roof member 31, a hinged roof supporting member 32 and two hinged side supporting members 33 and 34 which serve to support the roof and roof supporting member in the canopy assembled position shown in Figures 5 and 8. The roof member 31 is hinged supported to the brace 25 by a longitudinally extending hinge 35. In similar fashion the roof supporting member 32 is hinged supported to the roof by a longitudinally extending hinge 36. Both the roof member and the roof supporting member 32 as well as the side supporting members 33 and 34 are all made of rigid materials of construction such as sheet metal in order to provide for rigidity of the assembled canopy.

The roof supporting member 32 is further connected to the roof by biasing springs 38 and 39 at opposed ends of the roof. These springs serve to bias the roof supporting member to a perpendicular position with respect to the roof as shown in Figure 5. This biasing construction aids in the maintenance of a locked interengagement of the roof supporting member with the side supporting members as will further appear. Both biasing springs 38 and 39 are secured at one end to the roof member and at the other ends to the roof supporting member to effect this biasing operation.

The mechanism for locking the roof supporting member upon the side supporting members is best shown in Figures 5, 8, 12 and 13. Thus, the roof supporting member 32 will be seen to be a generally dish-shaped construction by virtue of a peripherally extending flange 41 which extends around both sides and the bottom side. The side flange which is designated 41' is provided with a strip 42 which is spaced from the side flange to receive a protecting portion of the side supporting member and to provide for locking, as best shown in Figure 12. A lip 43 extends downwardly between the side flange 41' and the strip 42 and is adapted to receive a projecting tongue 44 of the side supporting member which fits underneath it as appears in Figure 13. The tongue 44 is provided at the corner portion of the side supporting member to provide for the interengaging relationship shown in said Figure 13.

Both side supporting members 33 and 34 are identical in construction as will be apparent in the drawings, and only the side supporting member 34 will be described. This member in addition to the tongue construction previously described, and shown in Figures 12 and 13, is provided with a support bar 47 in order to maintain the locked position and rigid relationship for the vending stand. The support bar 47 is pivotally connected by means of a pivot hinge 48 at a medial portion of the supporting side member as appears in Figure 5. The other end of the support bar 47 is provided with a hook portion 49 as appears in Figure 1. The hooked portion is adapted to fit within an eye 51 provided in the retaining member 52 shown in Figure 8. The retaining member 52, and likewise the retaining member 53, both shown in Figure

5 are further provided with receiving portions to receive the supporting bar when the canopy is in the knocked down position. A means for moving the side supporting member 34 from the knocked down position shown in Figure 1 to the roof supporting position shown in Figure 5 is effected by a hinge 54 which hinged connects the side supporting member to the corner post 24.

In order to lock the roof and the roof supporting member in the window covering position shown in Figure 1, a lock is provided. This lock is designated by the reference numeral 60 and is best shown in Figures 1, 9, 10 and 11. The lock comprises a handle 61 and a threaded shank 62 which fits through holes in the corner post 24 so that it may be rotated. A lock nut 63 is provided to tighten the lock. A hooked portion 64 is provided at one end and is of a size to fit through a slot 65 provided in the lower right hand corner of the roof supporting member as shown in Figure 9. In the position shown in Figures 9, 10 and 11 the roof and roof supporting member are locked in the window covering position with the lock nut shown adjusted tightly to effect the proper securing of the apparatus. Upon loosening of the lock nut 63, the handle 61 may be rotated one-quarter revolution to a counterclockwise position as shown in Figures 9 and 11 to permit the unlocking of the roof supporting member when the canopy is desired to be set up to the assembled position.

Use

30 The canopy assembly is shown in the knocked down or vending window covering position in Figure 1. From this position it is very simply and very quickly adapted to be set up in the canopy assembled position shown in Figures 2, 3, 5 and 8. This is of very great advantage to vending stand operators in changing their stands from one location to another.

35 From the position shown in Figures 1 and 4 the canopy may be simply set up by first removing the side supporting member rods 47 from the retaining brackets 52 and 53. When this is done, the side supporting members 33 and 34 are both moved away from the supporting brace 25 to a perpendicular position. When this relationship is attained, the side supporting rods 47 are hooked and locked to the retaining brackets 52 as shown in Figure 8 by insertion of the hooked portions 49 into the eyes 51. This operation firmly anchors the side supporting members in the perpendicular position.

40 The roof member 31 and the roof supporting member 32 are then released from the locked position by the rotation of the locking member 60. When these locking devices are rotated to present the hooked portion 64 over the slot 65, shown in Figure 9, the roof supporting member 32 will be released and will automatically move to a right angle or perpendicular position with respect to the roof member 31.

45 55 The roof member 31 together with the roof supporting member 32 may then be manually elevated to a raised position and swung about the hinge 35 to approach a locking and supporting position with respect to the side supporting members.

60 65 As the roof member and the roof supporting members are raised, the roof supporting member may be moved slightly away from the perpendicular position with respect to the roof about the hinge 36 and against the force of the biasing spring so that it may hook over the terminal tongue 44 of the side supporting members. In this operation the projecting flange 41 and the lip 43 are hooked over the tongue 44 as shown in Figures 12 and 13. By this operation the end of the side supporting members will be nested within the flange end 41' shown in Figure 12 and the supporting strip 42. This arrangement prevents lateral and vertical movement of the side supporting members with respect to the roof and roof supporting members and provides for a secure locking arrangement. The biasing spring helps to maintain this locking arrangement by biasing the roof sup-

porting member 32 to the perpendicular position and in the locked relationship with the side supporting member 34 as appears in Figure 5.

By the sequence of operations described above, it will be apparent that the roof may be locked with respect to the side supporting members by a very easy sequence of steps. The setting up of the canopy in the canopy assembled position can take place in a matter of seconds and as is apparent from the description above, no tools are required in this assembly.

Once the canopy has been assembled as mentioned above, the reversed operation or breakdown to the window covering position is very simply effected. The first step will be the disengagement of the roof supporting member from the tongue 44. This is accomplished by slightly lifting the roof and swinging back the roof supporting member against the force of the biasing spring 39. This effectively disengages the roof supporting member from the side supporting member and the roof will swing down of its own weight about the hinge 35. The roof and roof supporting member may then be very simply locked to the vending stand.

The locking operation is effected by inserting the hooked portion 64 of the lock shank 62 through the opening 65 in the roof supporting member and then turning the lock a quarter revolution to bear against the side of the roof supporting member. When this has been effected the lock nut 63 is tightened.

Both the side supporting members 33 and 34 will then be very simply locked in place. This is effected by swinging the side supporting member against the brace 25 to the position shown in Figure 1. In this position the supporting rods 47 may be placed in the retaining brackets 52 and 53 to effectively lock the side supporting members in place.

When the canopy is collapsed to the window covering position shown in Figure 1, all the parts are securely locked in place. This is of advantage through the very simple collapsing operation above described since no tools of any type are required to effectuate the collapsing and locking of the component parts. Further no protuberances or complicated equipment is presented and the simple nature of the apparatus and the operations employed are of great value in providing simply operated and constructed canopies for vending stands. Further, when the canopy is collapsed the parts are securely locked in position to withstand the vibration and rigor of travel when the stand is moved from one location to another. Also, the stand through the covering of the windows is protected against the hazards of weather, theft and vandalism.

Various changes and modification may be made in the canopy of this invention. It will be apparent that the canopy may be utilized in any desired structure and is not restricted to vending stands where it does, however, find particular advantage. Such changes and modifications as are apparent to those skilled in the art are within the teaching of this invention as defined by the claims appended hereto.

What is claimed is:

1. A collapsible canopy comprising a roof and a pair of spaced supporting side members, means for retaining said roof upon a vertical wall in hinged relation substantially flush with the bottom of the side members, means for supporting said side members at opposite sides of the roof upon the wall in hinged relation above the roof and engaging means on said side members for supporting the roof in elevated canopy assembled position, said side members being oppositely swingable with respect to said wall from a position substantially flush with the wall to a substantially perpendicularly extending roof supporting position.

2. A collapsible canopy comprising a roof and a pair of spaced supporting side members, means for retaining said roof upon a vertical wall in hinged relation, means

for supporting said side members at opposite sides of the roof upon the wall in hinged relation and engaging means on said side members for supporting the roof in elevated canopy assembled position, said side members being oppositely swingable with respect to said wall from a position substantially flush with the wall to a substantially perpendicularly extending roof supporting position, and means for retaining said side members against the wall in the flush position and for supporting said side member against movement in the perpendicularly extending roof supporting position comprising supporting rods engageable with retaining elements secured upon said wall.

3. A collapsible canopy comprising a roof member, a roof supporting member and a pair of spaced supporting side members, means for retaining said roof member upon a vertical wall in hinged relation substantially flush with the bottom of the side members, means for retaining said roof supporting member upon the roof member in hinged relation, means for supporting said side members upon the wall in hinged relation above the roof, and means on said side members engaging the roof supporting member in vertical position for supporting the same and the roof member in an elevated canopy assembled position.

4. A collapsible canopy comprising a roof member, a roof supporting member and a pair of spaced supporting side members, means for retaining said roof member upon a vertical wall in hinged relation substantially flush with the bottom of the side members, means for retaining said roof supporting member upon the roof member in hinged relation, said roof supporting member having means biasing it to a position perpendicular to the roof member, means for supporting said side members upon the wall in hinged relation above the roof, and means on said side members engaging the roof supporting member in vertical position for supporting the same and the roof member in an elevated canopy assembled position.

5. A collapsible canopy comprising a roof member, a roof supporting member and a pair of spaced supporting side members, means for retaining said roof member upon a vertical wall in hinged relation substantially flush with the bottom of the side members, means for retaining said roof supporting member upon the roof member in hinged relation, said roof supporting member having means biasing it to a position perpendicular to the roof member, means for supporting said side members upon the wall in hinged relation above the roof, and catch means on said side members engaging a hooked element on said roof supporting member for supporting the same in vertical position and the roof member in an elevated canopy assembled position.

6. A collapsible canopy comprising a roof member, a roof supporting member and a pair of spaced supporting side members, means for retaining said roof member upon a vertical wall in hinged relation substantially flush with the bottom of the side members, means for retaining said roof supporting member upon the roof member in hinged relation, said roof supporting member having means biasing it to a position perpendicular to the roof member, means for supporting said side members upon the wall in hinged relation above the roof, and catch means on said side members engaging a hooked element on said roof supporting member for supporting the same in vertical position and the roof member in an elevated canopy assembled position, said roof supporting member being disengageable from the side members and adapted to be lowered from the elevated to a lowered substantially vertical position.

7. A collapsible canopy comprising a roof member, a roof supporting member and a pair of spaced supporting side members, means for retaining said roof member upon a vertical wall in hinged relation substantially flush with the bottom of the side members, means for retain-

ing said roof supporting member upon the roof member in hinged relation, said roof supporting member having means biasing it to a position perpendicular to the roof member, means for supporting said side members upon the wall in hinged relation above the roof, and catch means on said side members engaging a hooked element on said roof supporting member for supporting the same in vertical position and the roof member in an elevated canopy assembled position, said roof supporting member being disengageable from the side members and adapted to be lowered from the elevated to a lowered substantially vertical position to cover a window in said wall, and means for locking said roof and roof supporting member.

8. A collapsible canopy comprising a roof member, a roof supporting member and a pair of spaced supporting side members, means for retaining said roof member upon a vertical wall in hinged relation substantially flush with the bottom of the side members, means for retaining said roof supporting member upon the roof member in hinged relation, said roof supporting member having means biasing it to a position perpendicular to the roof member, means for supporting said side members upon the wall in hinged relation above the roof, and catch means on said side members engaging a hooked element on said roof supporting member for supporting the same in vertical position and the roof member in an elevated canopy assembled position, said roof supporting member being disengageable from the side members and adapted to be lowered from the elevated to a lowered substantially vertical position to cover a window in said wall, and means for locking said roof and roof supporting member including a lock element operable from the back of the wall and locking the roof and roof supporting

5
10

member against a portion of the wall bounding said window.

9. A collapsible canopy comprising a roof member, a roof supporting member and a pair of spaced supporting side members, means for retaining said roof member upon a vertical wall in hinged relation, means for retaining said roof supporting member upon the roof member in hinged relation, said roof supporting member having means biasing it to a position perpendicular to the roof member, means for supporting said side members upon the wall in hinged relation, and catch means on said side members engaging a hooked element on said roof supporting member for supporting the same and the roof member in an elevated canopy assembled position, said roof supporting member being disengageable from the side members and adapted to be lowered from the elevated to a lowered substantially vertical position, said side members being oppositely swingable with respect to said wall from a position substantially flush with the wall to a substantially perpendicularly extending roof supporting position.
